UNITED STATES PATENT OFFICE.

WILLIAM E. MOREY, OF CHICAGO, ILLINOIS, ASSIGNOR TO RODGER BALLAST CAR COMPANY, OF CHICAGO, ILLINOIS, A CORPORATION OF MAINE.

DUMP-CAR-CONTROL MECHANISM.

Application filed November 10, 1923. Serial No. 673,876.

The present invention relates to dump door control mechanism.

More particularly the present invention relates to apparatus such as is used on dump cars for controlling the dumping of the lading in said cars. Certain dumping mechanisms as now known and used are open to objection by reason of the fact that lading is liable to lodge in parts of the operating mechanism, interfering with the proper functioning thereof and requiring considerable personal attention on the part of the operators of said mechanism.

A further objection to certain dumping mechanism as now known and used lies in the fact that certain of the parts thereof are liable to assume positions, due to strains received in service, from which they cannot be moved by operation of the operating mechanism commonly provided, requiring extra labor on the part of the operators.

An object of the present invention is to provide a simple structure applicable to designs of dump cars as now known and used which will avoid the difficulties above mentioned.

A further object is to provide simple and inexpensive means for preventing clogging of the operating mechanism of railway dump cars.

A further object is to provide stop mechanism for preventing the parts of the control means of railway dump cars from assuming inoperative positions. Further objects will appear as the description proceeds.

Referring to the drawings—

Figure 1 is a transverse sectional view of a railway dump car embodying the principles of the present invention.

Figures 2 and 3 are sectional views on an enlarged scale showing details of the dumping mechanism of the car illustrated in Figure 1.

Figures 4 and 5 are end and side elevations of certain stop mechanism forming part of the present invention.

Figure 6 is a plan view illustrating part of the mechanism for preventing clogging of the dump door operating mechanism.

The numeral 1 indicates a railway dump car of the selective type. Said car is provided with side walls 2—2 and a center sill 3. The center sill 3 is provided with a cope 4 and with shedding walls 5—5 for directing lading transversely of the car away

from the center sill 3. Mounted adjacent the side walls 2—2 are the sloping walls 6—6, which converge downwardly and inwardly of the car. Pivoted for movement about the axes 7—7 are dump doors 8—8 which co-operate with the walls 6—6 and shedding walls 5—5 to complete the closure for the bottom of the dump car 1. The movement of the dump doors 8—8 about the axes 7—7 is controlled by certain link 60 mechanism indicated as a whole by the numeral 9. Said link mechanism is controlled by the rotatable shaft 10 which in turn is controlled by the transversely extending shaft 11. The doors 8—8 may be 70 provided with stiffening members 12—12 for preventing buckling of said doors. Said swinging doors 8—8 are provided with intermediate doors 13—13 pivoted for movement about the axes 14—14. Movements of 75 the intermediate doors 13—13 about their axes 14—14 are controlled by the chains 15—15 which in turn are controlled by the longitudinally extending shafts 16—16. Movement of the doors 8—8 about their axes 80 7—7 will result in the dumping of lading from the car 1 between the tracks upon which the car is mounted. Movement of the doors 13—13 about their axes 14—14 will result in the dumping of lading outside 85 of the tracks.

The link mechanism 9, by means of which movement of the doors 8—8 is controlled, need not be described in detail herein, inasmuch as the details of said link mechanism do not constitute the present invention. It may be stated, however, that said link mechanism comprises two series of operating members, one series for each of the doors 8—8. Referring to Figure 2, it will be 90 noted that the rotatable shaft 10 has secured thereto a crank arm 17 which operates through a series of links 18, 19 and 20 to control the right hand door 8. Referring to Figure 3 it will be noted that the rotating shaft 10 has fixed thereto the crank arm 21, which operates through links 22, 23 and 24 to control movement of the left hand door 8. Rotation of the shaft 10 in one direction 100 will result in operation of the links 18, 19 and 20, and links 22, 23 and 24 to open both doors 8. Operation of the shaft 10 in the reverse direction will result in the operation of said links to close the doors 8—8. As 105 noted above, rotative movement of the shaft 110

10 is controlled by means of the transversely extending shaft 11.

The relative positions of the links when the doors are in fully opened positions and 5 closed positions are indicated by dotted lines and full lines, respectively, in Figures 1, 2 and 3. A considerable degree of movement between link 20 and door 8 will occur during movement from one of said positions to 10 the other of said positions. When lading is being dumped from the car there is a possibility that part of said lading will lodge between the link 20 and the door 8, interfering with the subsequent closure of said door 15 8. In order to prevent any such possible interference, the present invention contemplates the provision of certain protective means which will now be described.

The right hand door 8 has mounted thereon 20 near the swinging edge thereof the receptacle 25, which may be united to said door 8 by rivets or other preferred holding means. Said receptacle 25 provides a groove or channel 26 for the reception of a lip or guard 27 located adjacent the lower extremity of the link 20. The receptacle 25 provides means for connecting the link 20 to the door 8, said link 20 being pivotally connected to the receptacle 25 by means of the 25 pin 28. The lip 27 is adapted to ride at all times within the groove 26 provided by the receptacle 25 and will effectually prevent the lodging of lading in a position close to the pivotal connection between link 20 and door 8, thereby preventing such lading from interfering with the proper operation of said link 20 and door 8.

Non-rotatively mounted upon the operating shaft 10 is the stop member 29. Said stop member 29 includes the two arms 17 and 21, each of which is bifurcated for the reception of a link. Said arms 17 and 21 are connected by the sleeve portion 32 having a cylindrical exterior whereby said member 29 may be rotatably supported by the strap 32', the ends of which may be connected to any suitable part of the car frame. It need not be stated that the member 29 is non-rotatably mounted on shaft 10. The bifurcated arm 17 provides a pivotal connection for link 18 and is provided with an abutment means or stop 33 adapted to cooperate with the link 18 or other member of the link mechanism for the right hand door 8. The bifurcated arm 21 provides a pivotal connection for link 22 and is provided with an abutment means or stop 34 adapted to cooperate with link 22 or other member of the link mechanism for the left hand door 8. It will be clear, without detailed explanation that if, due to the strains encountered in service, the links constituting the operating mechanism for either or both of the doors 8-8 should tend to move 55 too close to the center of rotation of shaft 10, that is to say, if said links should tend to move to inoperative positions, such movement will be effectually prevented by the stops or abutment members 33 and 34, which will engage said links and prevent same 60 from moving to such inoperative positions. Said stops or abutment members 33 and 34 have the function, therefore, of holding the links for operating the doors 8-8 in proper spaced relation relative to the axis of rotation of the operating shaft 10.

It will be at once understood that the lip 27 on the link 20, inasmuch as it operates at all times within the confines of receptacle 25, will hold lading in spaced relation with the pivotal connection between said link 20 and the corresponding door 8, so that the danger of clogging between said link 20 and the corresponding door 8 will be substantially eliminated. Furthermore, by reason of the structure which holds the operating links always in proper spaced relation relative to the axis of rotation of the operating shaft 10, danger is eliminated of said links assuming inoperative positions due to strains 70 encountered in service.

Although a preferred embodiment of the present invention has been described in detail, it will be clear to those skilled in the art that many modifications may be made without departing from the spirit of the invention. It is intended in this patent to cover all such modifications that fall within the scope of the appended claims.

I claim:

1. In dumping mechanism, in combination, a swinging dump door, a member for moving same to closed position, said member being pivotally connected to said door adjacent to the swinging edge thereof at a position adjacent to which lading is likely to pass in the dumping operation of said mechanism, said member and said door being provided with cooperating guard members operative at all relative positions of said member and said door to keep lading at a relatively great distance from the region of pivotal connection of said member to said door.

2. In a railway dump car, in combination, a swinging door, a member for moving said door to closed position, said member being pivotally connected to said door, at a point adjacent which lading is likely to pass in the dumping operation of said car, said member and said door being provided with interfitting parts for keeping lading away from the region of said pivotal connection, said interfitting parts comprising a slotted member secured to said door and a toe-like member projecting a material distance from the point of pivotal connection between said closing member and said door.

3. In dump car construction, in combination, a swinging door, a shaft mounted par-

allel with the pivotal axis of said door, link mechanism between said shaft and said door for controlling the operation of said door, means upon said shaft for preventing said link mechanism from assuming inoperative positions, said link mechanism and said door being provided with interfitting parts for keeping lading away from the region of pivotal connection between said link mechanism and said door, said interfitting parts comprising a slotted member secured to said door, and a toe-like member projecting a material distance from the point of pivotal connection between said link mechanism and said door.

4. In a dump car, a pair of dump doors pivoted about axes lying longitudinally of said car, an operating shaft disposed longitudinally of said car and a pair of systems of links connecting said shaft with each of said doors, and a fitting for said shaft provided with abutment means for preventing said links from getting out of operative position.

sition, said fitting comprising a member provided with a pair of bifurcated arms, said arms being provided with abutment portions for controlling said links. 25

5. In a dump car, in combination, a pair of swinging doors pivoted about axes disposed longitudinally of said car, an operating shaft disposed longitudinally of said car, a system of links connecting said shaft with one of said doors, a second system of links connecting said shaft with the other of said doors, said systems of links being spaced 30 apart, and a fitting mounted upon said shaft, said fitting being provided with a pair of bifurcated arms for operating said links, each of said bifurcated arms being positioned to embrace one of said systems of links and 35 being provided with stop means for preventing said links from moving to an inoperative position.

Signed at Chicago, Illinois, this 29th day of October, 1923.

WILLIAM E. MOREY
